STANCHION FOR CAR TOP LUGGAGE CARRIER

Frederick A. Helm, Detroit, Mich., assignor to Helm Accessories, Inc., Detroit, Mich., a corporation of Michigan

Filed May 24, 1962, Ser. No. 70,270

Term of patent 7 years

(Cl. D14—27)

FIG. 1 is a side elevation of a stanchion for a car top carrier embodying my novel design.

FIG. 2 is a side elevation taken from the opposite side of FIG. 1.

FIG. 3 is an end view taken from the left-hand end shown in FIG. 1.

FIG. 4 is an end view taken from the right-hand end shown in FIG. 1.

FIG. 5 is a sectional view taken along the line 5—5 in FIG. 1.

The dominant features of my design reside in the portions shown in full lines.

I claim:

The ornamental design for a stanchion for car top luggage carrier, as shown and described.
